UNITED STATES PATENT OFFICE.

JAMES P. MONTGOMERY, OF WICHITA, KANSAS, ASSIGNOR OF FORTY-NINE ONE-HUNDREDTHS, TO G. L. EDWARDS, OF WICHITA, KANSAS.

PUMP.

No. 845,965.

Specification of Letters Patent.

Patented March 5, 1907.

Application filed July 19, 1905. Serial No. 270,362.

To all whom it may concern:

Be it known that I, JAMES P. MONTGOMERY, a citizen of the United States, residing at Wichita, in the county of Sedgwick and State of Kansas, have invented a new and useful Pump, of which the following is a specification.

The invention relates to improvements in pumps.

10 The object of the present invention is to improve the construction of pumps and to provide a simple and comparatively inexpensive one designed particularly to be operated by a windmill or by hand and adapted to render the operation uniform and to prevent the jar and vibration incident to the operation of an ordinary pump by a windmill.

A further object of the invention is to provide a pump of this character having adjustable counterbalancing means adapted to partially counterbalance the weight of the pump or sucker rod in order that on the upward stroke it will be necessary only to lift a portion of the weight of the said rod and also to 25 divide the weight, so that a portion of the same will be utilized for lifting the water and a portion for balancing the operation of the pump to lessen the jar and vibration.

The invention also has for its object to provide a pump which will be effective in lifting water on the downstroke and in which there will be no unnecessary lifting of the water on the upstroke, thereby reducing the labor of operating the pump to a minimum.

35 Furthermore, the invention has for its object to provide a pump adapted for pumping either water or oil and capable of maintaining a constant agitation of the liquid to prevent sand from settling in the valve and clogging the pump.

With these and other objects in view the invention consists in the construction and novel combination and arrangement of parts hereinafter fully described, illustrated in the 45 accompanying drawings, and pointed out in the claims hereto appended, it being understood that various changes in the form, proportion, size, and minor details of construction within the scope of the claims may be rejected to without departing from the spirit or sacrificing any of the advantages of the invention.

In the drawings, Figure 1 is an elevation, partly in section, of a pump constructed in

accordance with this invention. Fig. 2 is a 55 vertical sectional view of a portion of the same. Fig. 3 is an enlarged sectional view illustrating the construction of the cylinder and the hollow piston of the pump. Fig. 4 is a detail sectional view illustrating the construction of the coupling for connecting the pump or sucker rod with the hollow piston. Fig. 5 is a detail perspective view of the horizontal bar which forms a support for the adjustable fulcrum of the counterbalancing-lever. Fig. 6 is a detail view of the adjustable fulcrum.

Like numerals of reference designate corresponding parts in all the figures of the drawings.

1 designates a pump-cylinder, receiving a hollow piston 2 and having a lower interiorly-threaded end 3, which is engaged by an upper exteriorly-threaded end 4 of a valve-seat 5. The valve-seat 5, which consists of a short tube, depends below the lower end of the cylinder and is provided at its upper end with a concave seat for the reception of a ball-valve 6, and the upward movement of the latter is limited by a stop, which preferably consists of a transverse pin 7, located above the ball and piercing the opposite sides of the pump-cylinder. Any other suitable means may be employed for limiting the upward movement of the ball-valve, which closes on the downstroke of the hollow piston, as hereinafter more fully explained.

The pump-cylinder may be secured within a well casing or pipe 8 by screw-threads or any other suitable means; but the extended 90 portion of the tubular valve-seat is preferably provided with a shoulder 9 for engaging an elastic gasket 10 arranged on the tubular portion between the said shoulder 9 and a lower metallic washer 11. The lower portion 95 12 of the tubular valve-seat is provided with exterior threads for the reception of a tubular shank or nut 13, which is interiorly threaded to engage the tubular valve-seat and which is provided with a plurality of strips 14, disposed substantially at right angles to each other and having bowed sides adapted to engage the interior of the well pipe or casing for holding the shank or nut against rotation. The upper end of the pump-cylinder is provided with opposite notches 15, adapted to be engaged by a suitable tube for rotating the pump-cylinder, and the rotation of the latter

is adapted to compress the inner portion of the elastic gasket, and thereby expand the outer portion and force the same into frictional contact with the well pipe or casing. 5 By this means the pump-cylinder is securely locked within the well pipe or casing and may be arranged at any desired point in the same. This construction also permits the pump-cylinder to be readily loosened for removal or adjustment. The pump-cylinder is also preferably provided at its upper end with an interiorly-arranged annular groove adapted to receive a suitable packing 16 for engaging the hollow piston. 15 The hollow piston has an interiorly-threaded lower end 17 for the reception of a reduced exteriorly-threaded portion 18 of a tubular valve-seat 19, which receives a ball-valve 20, and the upward movement of the latter is 20 limited by a transverse pin 21, which pierces the opposite sides of the hollow piston, or any other suitable form of stop may be employed for this purpose. The upper portion of the hollow piston is provided with outlet-openings 22, preferably consisting of circular apertures, as clearly illustrated in Fig. 3 of the drawings. The upper end of the hollow piston receives a coupling member 23, consisting of two sides and a top connecting portion 24, 25 which is provided with an enlarged opening 25 for the reception of a bolt 26. The bolt 26 engages a similar reversely-arranged coupling member 27, which is secured to a pump or sucker rod 28, a jam or lock nut 29 being 30 preferably interposed between the two coupling members to secure the bolt firmly to the coupling member. The enlarged opening of the lower coupling member permits the necessary lateral movement or play of the pump or sucker rod. The lower end of the pump or 35 sucker rod is spaced slightly from the upper end of the hollow piston to facilitate the discharge or escape of water from the latter, and on the downstroke of the piston the water 40 shoots upward, the valve 6 being closed automatically and the valve 20 being similarly opened. On the up or ineffective stroke of the piston the upper valve 20 closes, and the lower valve 6 opens to permit the entrance of 45 water into the pump-cylinder. It will thus be seen that the reciprocation of the pump or sucker rod and the hollow piston produces a constant agitation of the liquid, which will be found of great advantage where the liquid is 50 laden with sand, as the agitation will prevent the sand from settling on the valve-seats and clogging or otherwise interfering with the operation of the pump. This operation renders the pump specially advantageous in oil-producing countries. 55 The pump or sucker rod and the hollow piston are of uniform diameter in order to present no projecting portions or shoulders, so that there will be no unnecessary lifting of 60 water on the upstroke, the only water lifted

being that contained within the hollow piston. This construction permits the pump or sucker rod to pass upward through the water without any material resistance, and the pump is thereby adapted to be operated with the 70 minimum amount of power. The upper end 29a of the well pipe or casing is screwed within the lower end of a pump barrel or casing 30, which is secured at its lower end upon a suitable platform or support 31 and is provided at a point intermediate of its ends with a discharge-spout 32. The pump or sucker rod extends through the upper end of the pump barrel or casing, which is provided at the top with a suitable packing 33 and a 80 nut or stuffing-box 34. A pump-handle 35, which is fulcrumed on an arm 36 of the pump barrel or casing, is connected with the upper portion 37 of the pump-rod. The pump-rod may be either tubular or solid and when 85 constructed of tubular metal is closed at its lower end, so that on the downstroke it will force the body upward through the well-casing in the space between the same and the pump or sucker rod. The weight of the 90 pump or sucker rod is thereby utilized to raise the body. In order to avoid the jar and vibration of an ordinary pump by a windmill and to render the operation of the pump more uniform and also to enable the 95 pump to be operated with less power, only a portion of the weight of the pump-rod is lifted on the upstroke by the operating power. The weight of the pump is thereby 100 divided, a portion being utilized to assist the operation of the pump in expelling or raising the water and the other portion being utilized to produce a uniform operation of the pump. This is effected by means of a counterbalancing-lever 38 and a weight 39. The 105 upper portion 37 of the pump-rod is shaped into a bar and is provided at intervals with perforations, the upper end of the pump-handle being connected with the portion 37 at an intermediate point and the upper end 110 of the said portion 37 being designed to be connected with a windmill in the usual manner.

The lever 38 is connected at its inner end by a pivot 40 with the pump-rod, which is 115 provided with an enlargement for the reception of the inner end of the lever. The lever is pivoted at an intermediate point by a bolt 41 or by any suitable fastening device to the upper end of an adjustable fulcrum-bar 42, 120 which is adjustably mounted at its lower end on a horizontal supporting-bar 43. The ends of the fulcrum-bar 42 are bifurcated and embrace the sides of the lever and the supporting-bar 43. The inner end of the 125 supporting-bar 43 is bifurcated and is secured by a bolt 44 or any suitable fastening device to a bracket 45, consisting of a web or flange formed integral with the pump barrel or casing and having a projecting portion 130

46, forming a shoulder and extending beneath the lower edge of the supporting-bar 43, as clearly illustrated in Figs. 1 and 2 of the drawings. The outer end 47 of the supporting-bar 43 is provided with a collar which embraces the upper end of a tube 48, and the latter is arranged over a well or casing 49, in which the weight 39 operates. The weight 39 is connected by a rod 50 with the outer end of the lever 38, and when the lever is oscillated by the reciprocation of the pump or sucker rod the weight will move up and down in the well or casing 49 and partially counterbalance the pump or sucker rod. A weight of any desired size may be employed, and by moving the fulcrum-bar 42 inward and outward the relative lengths of the inner and outer arms of the lever 38 may be varied to secure the desired leverage. By this means the counterbalancing effect of the weight may be varied to adapt the pump to the character of windmill or other operating power with which the pump is used and also to render the operation of the pump easy by hand. The upper end of the pump-cylinder is interiorly threaded to receive a pair of threaded rings or sleeves 51^a and 52, which are spaced apart to form a groove for the said packing 16. The inner or lower sleeve 52 also forms an interiorly-arranged shoulder, which is adapted to be engaged by a tool for extracting the pump-cylinder.

In order to prevent the tubular valve-seat 5, which is threaded into the lower end of the pump-cylinder, from accidentally unscrewing while expanding the elastic gasket, the valve-seat 5 is further secured to the lower end of the pump-cylinder by a transverse pin 53, which pierces the opposite walls of the valve-seat and the pump-casing, as clearly illustrated in Fig. 3 of the drawings. Any other suitable means may be employed for preventing the valve-seat from accidentally unscrewing when the pump-cylinder is rotated for expanding or contracting the rubber gasket.

It will be seen that by making the pump or sucker rod effective on the downstroke and by dividing the weight of the pump-rod a windmill or other operating power will perform substantially the same work on each stroke of the pump-rod. The operation of the windmill or other machine is thereby rendered uniform and the jars and vibrations incident to the ordinary windmill and pump are avoided. This will increase the life of both the pump and the windmill. The adjustment of the fulcrum of the lever will enable exactly the same amount of work to be performed on each stroke of the pump-rod.

Having thus fully described my invention, what I claim as new, and desire to secure by Letters Patent, is—

1. The combination with a pump having a pump-rod, of a well or casing spaced from the pump-rod, a tube extending upward from the well or casing, a supporting-bar extending from the pump to the tube, a fulcrum mounted on the supporting-bar, a lever connected to the pump-rod and secured at an intermediate point to the fulcrum, a weight operating in the said well or casing, and connecting means extending through the tube from the weight to the lever. 65

2. In a pump of the class described, the combination of a pump-casing provided with a bracket having an extended portion forming a shoulder, a pump-rod, a supporting-bar secured to the bracket and supported by the shoulder thereof, a fulcrum-bar mounted on the supporting-bar, a counterbalancing-lever mounted at an intermediate point on the fulcrum-bar and connected at one arm with the pump-rod, and a weight connected to the other arm of the lever. 80

3. In a pump of the class described, the combination of a pump-casing provided with a bracket, a pump-rod, a supporting-bar secured at one end to and supported by the bracket, a fulcrum adjustably mounted on the supporting-bar, a lever mounted at an intermediate point on the fulcrum and connected at one arm with the pump-rod, a tube connected with the outer portion of the supporting-bar, a weight, and means extending through the tube for connecting the weight with the lever. 85

4. In a pump of the class described, the combination with a well tube or casing, a pump-cylinder having a valve, a hollow piston operating in the pump-cylinder and also provided with a valve and having a water-outlet above the cylinder, a pump-rod connected with the hollow piston and spaced from the well tube or casing, said pump-rod being closed at the lower end and being of uniform diameter with the piston, and means for operating the pump-rod. 105

5. In a pump of the class described, the combination of a well tube or casing, a pump-cylinder secured within the well tube or casing and having a valve, a hollow piston operating in the pump-cylinder and provided with a valve and also having a water-outlet above the cylinder, a pump-rod of uniform diameter with the hollow piston and connected therewith, said pump-rod being closed to the passage of water, and means for operating the latter. 110

In testimony that I claim the foregoing as my own I have hereto affixed my signature in the presence of two witnesses.

JAMES P. MONTGOMERY.
